UNITED STATES PATENT OFFICE

EUGENE A. ROBERTS, OF AKRON, OHIO

DESIGN FOR A TIRE

Application filed July 8, 1931. Serial No. 40,461. Term of patent 14 years.

To all whom it may concern:

Be it known that I, EUGENE A. ROBERTS, a citizen of the United States, residing at Akron, in the county of Summit and State of Ohio, have invented a new, original, and ornamental Design for Tire, of which the following is a specification, reference being had to the accompanying drawings, forming a part thereof:

In the drawings:

Figure 1 is a perspective view of the tire

of my new design a section being illustrated in solid lines; and

Figure 2 is a cross-section on the line 2—2 of Figure 1.

Both sides of the tire design are the same as the design shown on the side of the tire of Figure 1.

I claim:

The ornamental design for a tire as shown and described.

EUGENE A. ROBERTS.
